TRIM FOR A VEHICLE CAB

Harvey F. Dick, Chagrin Falls, Ohio, assignor to White Motor Corporation, Cleveland, Ohio, a corporation of Ohio

Filed Feb. 23, 1968, Ser. No. 10,696

Term of patent 14 years

Int. Cl. D12—14

U.S. Cl. D14—6

FIG. 1

The elements shown in broken lines are only included for illustrative purposes.

I claim:

The ornamental design for a trim for a vehicle cab, as shown and described.
